UNITED STATES PATENT OFFICE.

CHARLES E. GALVIN, OF SPRINGFIELD, OHIO, ASSIGNOR TO THE RIDGELY TRIMMER COMPANY, OF SPRINGFIELD, OHIO, A CORPORATION OF OHIO.

DESIGN FOR A FRAME FOR PAPER-TRIMMING TOOL.

Application filed September 4, 1924. Serial No. 10,673. Term of patent 14 years.

To all whom it may concern:

Be it known that I, CHARLES E. GALVIN, a citizen of the United States, residing at Springfield, in the county of Clark and State of Ohio, have invented a new, original, and ornamental Design for Frame for Paper-Trimming Tool, of which the following is a specification, reference being had to the drawing forming part thereof.

Fig. 1 is an elevation of the forward side

of a frame for paper trimming tool showing my new design.

Fig. 2 is an elevation of the rear side of the same.

Fig. 3 is a top plan view of the same.

I claim:

The ornamental design for a frame for paper trimming tool as shown.

CHARLES E. GALVIN.
